UNITED STATES PATENT OFFICE.

AUSTEN M. CURTIS, OF EAST ORANGE, NEW JERSEY, ASSIGNOR TO WESTERN ELECTRIC COMPANY, INCORPORATED, OF NEW YORK, N. Y., A CORPORATION OF NEW YORK.

SUBMARINE SIGNALING SYSTEM.

Application filed September 17, 1925. Serial No. 56,825.

This invention relates to submarine signaling systems and more particularly to submarine signaling systems in which the terminal equipment is arranged and designed 5 to operate to permit the transmission of signals over a submarine cable at high speeds.

It is an object of the invention to provide terminal equipment which improves 10 the legibility of the signals transmitted at high signaling speeds.

It has heretofore been proposed to use auxiliary apparatus at the terminal of a submarine cable designed to operate upon 15 the wave form of the signals and to so shape these wave forms as to increase the legibility of the signals as recorded at the terminal. Devices of this sort are generally referred to as shaping networks or shaping elements. 20 Combinations of apparatus for this particular purpose in connection with submarine cables are disclosed in applicant's Patents 1,586,970 and 1,586,972, both issued June 1, 1926.

25 The present invention is in the nature of an improvement on these shaping networks or elements and is particularly useful in handling code signals from 30 to 60 cycles per second or higher.

30 In accordance with a feature of the invention, the above stated object is attained by providing a special shaping element cooperating with the usual sending condenser at the transmitting terminal of the cable and a special shaping element in combination with certain of the previously used shaping elements of the receiving apparatus.

35 In accordance with this feature, the special shaping element which cooperates with the sending apparatus takes the form of an impedance which has a low value as compared with the characteristic impedance of the cable and which is in effect, a shunt path to earth, on both the cable and its 40 associated transmitter and shunted sending condenser. At the receiving end of the cable, the novel shaping element takes the form of a highly damped anti-resonant circuit which is connected in series with the

signaling current path and tuned to a frequency somewhat below the signaling frequency.

In accordance with another feature of the invention and cooperating with the shaping element referred to as at the receiving end 55 of the system, there is provided an auto-transformer which is associated with the receiving circuit through a combination of resistances which also performs a shaping function for currents of a somewhat different range of frequencies than those for which the anti-resonant tuned circuit is effective.

These and other features of the invention will more clearly appear from the following description and the accompanying drawings, in which—

Figs. 1 and 2 when placed side by side show diagrammatically a complete sending and transmitting equipment in accordance 70 with the invention, such as is located at one terminal of the cable;

Fig. 3 shows a section of loaded conductor;

Figs. 4, 5 and 6 are diagrammatic representations of various electrical conditions which occur in the system and will be used in explanation thereof;

Figs. 7, 8 and 9 show modified forms of the receiving equipment, and

Figs. 10 and 11 show modified transmitting arrangements.

Due to the invention of an improved form of submarine cable and particularly to an improved loading material and methods of applying it to a cable it has become possible to operate at much higher signaling speeds than heretofore. This has necessitated the design and invention of new receiving and sending equipment, as well as the new shaping networks illustrated and claimed in the applications previously referred to.

As will more clearly appear from the following description, the present invention is concerned with the further improvement in shaping networks and shaping elements as applied to this recently invented equipment. The new result obtained by virtue of the

present invention is, as above pointed out, the more complete and accurate shaping of the signals to permit the satisfactory transmission of code signals up to 60 cycles or higher.

In the operation of submarine telegraph cables, the signal is formed by impressing positive and negative impulses upon the cable in various combinations and, as a result, 10 there is always some limiting frequency of transmitted impulses above which the received signals will be unintelligible. This limiting frequency may be called the limiting signaling frequency and is expressed in 15 cycles per second. By "signaling frequency" is meant the number of dot impulses transmitted per second when a succession of alternate dot and dash impulses is sent at the designated frequency of operation.

20 These various combinations of positive and negative impulses with periods of zero current may have frequency components anywhere within the range of from zero to infinity. However, in order to obtain sufficiently well formed signals at the receiver, such a wide range of frequencies is not actually required. Satisfactory results may be obtained provided all of the component frequencies up to about one and one-half times 25 the signaling frequency are properly transmitted. Thus, for signaling frequencies of 60 to 70 cycles, it is important to transmit frequency components up to about 100 cycles and it is particularly desirable to provide 30 adequate shaping for these higher frequencies especially when it is desired to transmit code messages where accuracy is essential.

Referring now to the drawings, it will be 35 noted that the sending and receiving equipment at one terminal of the cable is, in general, similar to that disclosed in the applications hereinbefore referred to in that it consists of the usual sending equipment involving, in addition to an instrumentality 40 for placing impulses on the cable, a sending condenser 19 with the usual shunt resistance 20, and the receiving equipment, in addition to the shaping elements, includes a four-stage amplifier of the vacuum tube type 45 working into a recording device which may be a specially designed high speed siphon recorder.

In order to point out the construction and 50 cooperation of the novel shaping elements of the present invention with the usual transmitting and receiving equipment, the terminal apparatus will now be described in detail and the relation of the novel elements thereto will be pointed out as the description 55 proceeds.

Referring now to Fig. 1, a single core 60 submarine cable 5 is terminated in a twin core section of submarine cable 6. One core 7 of the twin core section 6 is connected at one end to the single core cable 5 and at the

other end to a switch 8 by means of which it can be connected in its upper position to terminal 3 of the signal receiving apparatus "R" extending to the right of line X-X and in its lower position to the transmitting 70 apparatus "T". The other core 9 of the twin core section 6 is connected at the sea end through a resistance 10 to a conductor in contact with the sea water. In the particular arrangement shown, the resistance is 75 connected to the cable armor wires at point 11 and a conventional ground connection, shown by dotted lines, is used to indicate that the armor wires are grounded. The core 9, together with the network 10 grounded at the point 11, constitutes a cable balancing return circuit. The shore end of core 9 is connected to terminal 4 of the receiving apparatus "R".

A type of core suitable for both the single 85 core cable 5 and the twin core section 6 is illustrated in Fig. 3. The core comprises a copper conductor 14 provided with a wrapping 15 of a nickel-iron alloy, as described and claimed in patent to G. W. Elmen 90 1,586,887, issued June 1, 1926. The advantage of using this loading material is that its permeability at small magnetizing forces of the order of 0.01 to 0.10 gauss is from 10 to 20 times that of iron, that is, from 2000 to 95 4000. Over the wrapping of nickel-iron alloy, an insulating layer 16 of gutta percha or similar material is applied. The cable, with which the terminal apparatus, herein described, is intended to operate, when protected by armor wires in accordance with standard submarine cable practice, has a characteristic impedance for the higher frequencies involved in signaling of approximately 400 ohms, and this impedance is substantially a pure resistance.

The transmitting equipment "T" comprises a positive and negative impulse transmitter 17, series resistance 18 of 10 to 50 ohms, and condenser 19 of 20 to 75 microfarads with shunting resistance 20 of 5,000 to 100,000 ohms. As hereinbefore explained, the transmitting equipment "T" may be connected to the core 7 of the twin core section 6 by means of switch 8 in its lower 110 position. One terminal of the transmitting equipment is thus connected to the core 7, while the other terminal is grounded at a beach earth 2 or through a short length of low resistance conductor at an extra earth 115 at sea. According to one feature of this invention a comparatively low resistance 21 of 50 to 200 ohms is connected between the terminals of the transmitting equipment, that is, between the core 7 and earth 2. The 120 function of this low resistance shunt will now be explained.

Although the characteristic impedance of the cable is, as stated, approximately 400 ohms for voltages of the higher frequencies 125

involved in signaling, it is evident that for the voltages of very low frequencies this can not be the case. For example, at zero frequency, the characteristic impedance of the 5 cable is its direct current resistance; and in the case of an actual cable between New York and the Azores, this resistance is about 4600 ohms. The principal difficulty in correcting the distortion of this cable for signaling speeds above 30 cycles per second, lies in reducing sufficiently the relatively enormous amount of signaling components of the lower frequencies which are transmitted over the cable. This requires the utilization 10 to the fullest extent of shaping at both the transmitting and receiving terminals of the cable. The shunt resistance 21 aids materially in accomplishing this result and is a novel and efficient shaping element.

15 The immediate purpose of the shunt resistance 21 is to prevent the variable cable impedance from having any appreciable effect on the circuit consisting of the sending battery 17, battery resistance 18, shunted condenser 19, and cable and shunt resistance 21. In practice, it is found that this purpose is sufficiently well accomplished if resistance 21 has a value of from 50 to 200 ohms. The effect of resistance 21 is to 20 cause the application to the cable of the voltage wave form produced by charging the condenser 19 through a practically constant resistance. When, as previously was the practice, the resistance 21 is omitted, the voltage applied to the cable is modified by 25 the changing impedance of the latter in a direction to react unfavorably against the effect of the series condenser. This may be made more plain if we compute the voltages applied to the cable by various component frequencies of the signal. In these computations the shunt 20 on the condenser 19 has been neglected as it is not necessary to an understanding of the effect of the cable shunt 21. The measured impedance of the 30 actual loaded cable hereinbefore mentioned at various frequencies is given in the following table, where in F is the frequency, R the resistance component of the impedance, X the reactive component of the impedance, and Z the absolute value of the impedance in ohms.

F	R-jX	Z
3	500-j300	584
5	450-j200	493
10	410-j160	440
20	385-j75	390
40	375-j34	376
80	380-j30	381

55 The voltage applied to the cable, for an assumed sinusoidal voltage of 10 volts applied to the sending condenser at different frequencies, has been computed for two

cases, one in which the resistance shunt 21 was not used, and the other in which the shunt 21 had a resistance of 50 ohms. The results of this computation are shown graphically in Fig. 5 where curve C represents the 70 voltage frequency characteristic of the cable without shunt 21 and curve D, when shunt 21 is used.

The efficiency of the sending condenser may be judged by the effect it has in lowering the applied voltages at the lower frequencies. For efficient operation, it is essential that the voltage of the lower frequency components be reduced in amplitude to a greater extent than the higher frequency 80 components. It is apparent from curve C that without the shunt 21, the sending condenser is practically without effect at frequencies above 20 cycles and may be said to have negligible efficiency over this range, 85 while with the resistance 21 in circuit, the relation between the voltage applied to the cable and the frequency of the applied voltage, is practically a straight line up to 80 cycles per second. The efficiency of the two 90 shaping circuits may be roughly expressed as the relation in each case between the voltage impressed on the cable for the maximum frequency signal component and some other lower frequency which it is necessary to suppress. In the case of the ordinary condenser circuit, the voltage at 80 cycles is two and one-half times that at 5 cycles; while in the case where the shunted condenser 21 is used, the voltage at 80 cycles is eleven 100 times that at 5 cycles. It is thus seen that the sending circuit employing the shunt resistance 21 is much superior to that of previously known arrangements.

This method of transmitting end shaping 105 is particularly valuable, since it does not cause oscillation of the transmitted voltage, such as would be the case if an attempt were made to produce the same sort of an effect by means of an inductive shunt.

A similar transmitting equipment (not 110 shown) is provided at the distant end of the cable for transmitting to the receiving apparatus "R," and need not be further described.

The twin core section 6 is connected to the receiving equipment through a novel network which is illustrated by the portion of Fig. 1 between lines X-X and Y-Y. This termination consists of a shielded transformer 25, the secondary winding 26 of which is connected to the input circuit of the amplifier of Fig. 2. The primary winding 27 is connected to coupling resistance 28 by means of an auto-transformer 30. Resistance 28 is variable up to a maximum of 10,000 ohms. Resistance 29 is variable up to 100,000 ohms. Connected in series with the core 7 is a variable condenser 31 of 0.1 to 10 microfarads shunted by a variable re-

stance 32 of 10,000 to 2,000,000 ohms forming net work N^1 . This network is used to control the amplitude and phase of the lower frequency components of the signaling current. An anti-resonant network N^2 consisting of a variable condenser 33 of 0.1 to 5 microfarads, inductance 34 of 50 to 150 henrys, and a shunt resistance 35 of 1000 to 20,000 ohms, is also connected in series with the core 7 and network N^1 . This network N^2 is tuned to a frequency below the signaling frequency for which the rest of the system is adjusted and is used to reduce the amplitude of this and adjacent components of the signaling current and at the same time maintain a high impedance termination for the cable at these frequencies. The adjustment of the resistance 35 is customarily low enough to insure that this network is highly damped, and does not superpose an oscillation on the signal. Resistance 35 is also useful in adjusting the very low frequency components of the signal that is those below the range in which condenser 33 and the inductance of coil 34 are effective.

Another network N^3 consisting of a condenser 36 of 0.1 to 4 microfarads and inductance 37 of 1 to 10 henrys, is also connected in series with the conductor 7 and the two networks N^1 and N^2 . This network is sharply tuned and is used to eliminate a single interfering frequency outside the range of frequencies essential to signaling. This network is only used when such interfering frequency is present, and can be removed from the circuit by closing switch 38. Such interfering frequency may come from a number of sources, such as, for example, an electric railroad located in the neighborhood of the terminal station.

Auto-transformer 30 is variably connected to the input winding 27 of transformer 25 by way of conductor 40. The point 41 of the primary winding is connected to the junction point of resistances 28 and 29. The secondary winding 26 of transformer 25 is surrounded by shield 42 which is connected to the locally grounded terminal of winding 26.

The auto-transformer 30 may be a coil of about 50 henrys inductance wound on a core of grade A iron dust rings. These rings have a permeability of approximately 55 and are described in an article by Messrs. Speed and Elmen, entitled "Magnetic properties of compressed powdered iron," published in the Journal of the American Institute of Electrical Engineers, Vol. 40, July, 1921, page 596. Resistance 29 is preferably of a high value so that its effect on the circuit is small; but at adjustments which allow the received signal to produce troublesome oscillations, this resistance may be used to increase the damping of the circuit and so reduce its tendency to oscillate. It should

be noted that the purpose of this auto-transformer is to increase the definition of the signal by partially suppressing a certain band of frequencies somewhat lower than the signaling frequency which, without this suppression, would cause the received wave to overshoot and distort signals beyond legibility. This is also the purpose of the series anti-resonant circuit N^2 ; but while the latter is adjusted to be effective at approximately one-third of the signaling frequency, the auto-transformer is usually adjusted to be effective at about two-thirds of the signal frequency. This is accomplished by the proper adjustment of the resistance 28 with relation to the primary inductance and primary to secondary turns ratio of auto-transformer 30. Transformer 30 is connected so that the induced secondary voltage opposes the voltage drop across resistance 28, but the adjustment is such that this opposing voltage is negligible except for the band of frequencies which it is desired to suppress.

As an illustration of the effect of these networks on the "arrival curve" produced by applying a steady voltage to the transmitting terminal of the cable, reference is made to the curves of Fig. 6 where curve E shows the shape of the received voltage at the secondary terminals of transformer 25 when network N^1 and resistance 28 alone are used. Curve F shows the effect on the received voltage of adding network N^2 , while curve G shows the effect of adding the auto-transformer 30. These curves would normally be superposed, if plotted to the same scale of ordinates; but for the sake of clearness they are plotted separately. Since it is necessary that the "arrival curve" approximate a square-topped wave in order that undistorted signals may be received, it is evident that the speed of transmission possible with the circuit employed for obtaining curve G, is much greater than the speed obtainable with either of the other arrangements.

A suitable design for transformer 25 is described in applicant's Patent 1,586,972, supra. The core is of the shell transformer type and is made up of strips of nickel-iron alloy. The winding is arranged to have very small distributed capacity. Both the primary and secondary windings are made up of pancake sections. By far the larger part of the winding space is occupied by the primary coil, sufficient space being occupied by the secondary coil to give a reasonable primary to secondary turns ratio when the smallest wire available is used for the secondary winding. The use of a high resistance secondary coil is permissible on account of the fact that the secondary coil works into practically an infinite impedance. Measurements on an actual transformer at a value of

- current of the order of that encountered in submarine signaling, show that its primary inductance is 6300 henrys and its direct current resistance is about 0.28 ohm per henry.
- 5 With the primary closed on its normal impedance, the leakage inductance measured from the secondary terminals is of the order of 50 henrys. The ratio of primary reactance to primary resistance is not less than 10 40 from four to twenty cycles per second. The capacity between the primary sections adjacent to the secondary shield and the secondary shield is of the order of 500 micro-microfarads.
- 15 The amplifier of Fig. 2 comprises four stages of electron discharge amplifiers with suitable coupling circuits and signal shaping networks. The first stage amplified A^1 is provided with a negative grid battery 50 of 20 three volts. The filament of all the amplifiers are grounded and heated by current from a six-volt battery under the control of rheostats, as shown in Fig. 2.
- The output circuit of amplifier A^1 is coupled to the shaping network 51 by means of resistance 52 which is adjustable in four steps up to a maximum of 192,000 ohms and condenser 53 of 50 microfarads capacity. In series with resistance 52 is space current 30 supply battery B^1 of 250 volts. The shaping network 51 consists of a primary variable condenser 54 of 0.01 to 0.20 microfarads capacity, secondary variable condenser 55 of 1000 micro-microfarads maximum capacity, adjustable resistance 56 of a maximum value of 300,000 ohms and inductance coil 57 of 10,000 henrys maximum inductance, and a copper resistance of about 45,000 ohms.
- 40 A type of coil which is suitable for auto-transformer 57 has a core consisting of permalloy strips built up in the manner of a shell type transformer core in which a small air-gap is included in the magnetic circuit at one end of the central leg. The winding consists of seven pancake sections, each 0.35 inch thick, and containing 8300 turns of No. 40 single silk covered copper wire having a resistance of about 6500 ohms per section. The total copper resistance is, therefore, about 45,000 ohms, while the total inductance is approximately 10,000 henrys. A coil of this type is described in applicant's copending application, Serial No. 690,709, supra.
- 55 The upper terminal of coil 57 is connected to the grid of amplifier A^2 . The grid of amplifier A^2 is maintained negative with respect to the filament by means of battery 58 of three volts.
- 60 The shaping network 51 is not primarily a resonant network but comprises an auto-transformer with an abnormally high primary resistance. This resistance is so high in relation to the primary reactance at all of the higher frequency components of 65 the signal that the current in the primary circuit is practically in phase with the voltage across it. However, the turns ratio of the transformer is so large that the secondary induced voltage for the higher frequency components of the signal adds considerably to the voltage transmitted conductively to the secondary terminals by the drop in potential across the primary resistance. The resulting characteristic of 70 75 this network 51 is that the lower frequencies are transmitted to the secondary terminals unchanged, while the higher frequencies have their voltage increased substantially. The phase components of the signal are 80 shifted approximately proportionately to their frequency. Under these circumstances, the phase shifts do not change the shape of the signal, but merely retard it bodily in time; but as the amplification is greater for 85 the higher frequencies than for the lower, the attenuation of the cable is partly compensated for. The primary condenser 54 and the secondary condenser 55 are used with caution principally for the purpose of 90 reducing the effect of interference higher in frequency than any of the essential components of the signal.
- The amplifier A^2 is coupled to shaping network 59 by means of resistance 60 which 95 is adjustable in four steps up to a maximum of 192,000 ohms and condenser 61 of 10 microfarads capacity. In series with resistance 60 is space current battery B^2 of 100 250 volts. Shaping network 59 consists of inductance coil 62 shunted by resistance 66 connected in series with condenser 63. The input circuit of amplifier A^3 is connected across the variable portion of potentiometer 64, the fixed portion of which in series with 105 grid polarizing battery 65 is connected in shunt to condenser 63. Inductance coil 62 has a maximum inductance of 100 henrys. Resistance 66 is variable up to a maximum of 200,000 ohms. Condenser 63 has a capacity of 0.01 to 0.2 microfarads. Negative polarizing battery 65 is of 4.5 volts. The 110 potentiometer 64 has a maximum resistance of 2 megoms.
- 115 Amplifier A^3 is coupled to network 67 by means of resistance 68 which is also variable in four steps up to a maximum of 192,000 ohms and condenser 69 of 10 microfarads. In series with resistance 68 is space current battery B^3 of 250 volts. The 120 shaping network 67 comprises inductance coil 70 and condenser 71 connected in series across resistance 72 and grid polarizing battery 73. Inductance coil 70 has a maximum inductance of 100 henrys and is shunted by a resistance 74 having a maximum value of 300,000 ohms. The condenser 71 is adjustable to a maximum of 0.2 microfarad.

Resistance 72 has a value of 2 megohms. The negative grid polarizing battery 73 has a potential of 40 volts.

- Space current for amplifier A⁴ is supplied by battery B⁴ of 250 volts. Amplifier A⁴ consists preferably of two vacuum tubes connected in parallel. For simplicity one only is shown. The output circuit of amplifier A⁴ including battery B⁴ extends through a receiving device 75 which may be a siphon recorder as indicated. In the arrangement shown, the indicating device 75 is located at a considerable distance from the amplifier and is connected thereto by means of a cable.
- 15 76. A second indicating device 77 which may also be a siphon recorder, as shown, is connected in series to the output circuit of the amplifier for monitoring purposes.

Networks 59 and 67 may be adjusted so as to consist of a resistance and capacity in series or inductance and capacity in series or a shunted inductance in series with a capacity, the voltage which is impressed upon the input circuit of the succeeding amplifier being that across the condenser in all cases. Each of the adjustments discriminates against interfering components having frequencies higher than those essential to signaling. In addition, the first adjustment produces a relative advance in phase of the higher frequency components of the signal with respect to the lower, that is, a shift in the same direction as that produced by the cable. The second adjustment may be such as to relatively retard the phases of the components up to a certain frequency and advance them beyond that frequency. The third adjustment may be such as to act in either manner depending upon the relative magnitudes of the three-circuit elements. The potentiometer 64 is used for the purpose of increasing the flexibility of the adjustments of the amplifier of Fig. 2, and in this way permitting the amplifier to operate satisfactorily over a large range of signaling speeds.

In the signaling arrangements known prior to the present invention, it was possible to satisfactorily shape code signals up to a signaling speed of 30 cycles per second, as hereinbefore mentioned. In order to determine the effect of the system upon the different frequency components of the signaling current, a terminating network, such as that shown in Fig. 7, was used in the system of Figs. 1 and 2 between the lines X—X and Y—Y. According to that arrangement, networks N² and N⁴ and auto-transformer 30 of Fig. 1 were omitted and no shaping was employed in the amplifier of Fig. 2. The network N¹ of Fig. 7 is identical with the corresponding network of Fig. 1 and consists of condenser 31 and variable resistance 32. The cable is coupled to the primary winding 27 of transformer

25 by means of variable coupling resistance 30. In place of the transmitter 17 at the sending end, various sine wave currents of different frequencies were impressed upon the cable through condenser 19 shunted by 70 resistance 20. The circuit elements were adjusted to have the following values: Sending resistance 18, 17 ohms; sending condenser 19, 60 microfarads; shunt resistance 20, 5000 ohms; receiving condenser 31 of 75 Fig. 7, 2 microfarads; shunt resistance 32 of Fig. 7, 400,000 ohms; coupling resistance 80 of Fig. 7, 1,500 ohms; voltage of sine wave source (R. M. S.), 10 volts.

With the circuit adjustments just given, 80 the curve A of Fig. 4 was obtained, showing that current of approximately 15 cycles was much less attenuated than either the lower or the higher frequencies. This marked difference in the amount of attenuation of the 85 various frequency components accounted for the distortion of the signals which prevented code reception at signaling speeds above 30 cycles.

In order to equalize the attenuation of the 90 various frequency components, the arrangement of Fig. 8 was substituted for that of Fig. 7 between the lines X—X and Y—Y in Fig. 1. A series resonant network N⁴ consisting of condenser 81, inductance 82, 95 and resistance 83 was connected between conductors 7 and 9 of the twin core section 6. Resistance 84 was connected in shunt to inductance 82. This network was tuned to offer low impedance to current having a 100 frequency of approximately 15 cycles. The circuit elements were adjusted to the following values: Sending resistance 18, 17 ohms; sending condenser 19, 60 microfarads; shunt resistance 20, 5000 ohms; receiving condenser 31, 1.4 microfarads; receiving resistance 32, 800,000 ohms; resistance 80, 1500 ohms; condenser 81, 11 microfarads; inductance 82, 6.5 henrys; resistance of inductance 82, 54 ohms; resistance 83, 110 300 ohms; resistance 84, 800 ohms.

With this arrangement, curve B of Fig. 4 was obtained which shows that the attenuation of the different frequency components is more nearly equalized by the arrangement of Fig. 8 than by that of Fig. 7.

The use of the series resonant shunt network N⁴ of Fig. 8 while effective in equalizing the attenuation of the various frequency components of the signaling current reduces the terminal impedance of the cable at the frequency to which the series resonant circuit is tuned and correspondingly lessens the impedance to adjacent frequencies. To overcome this difficulty, the arrangement of Fig. 9 was employed. In other words, the shunt series network N⁴ of Fig. 8 is replaced by the series anti-resonate network N² consisting of inductance 34, condenser 33 and resistance 35. With the arrangement of Fig. 125 130

9 substituted for that portion of Fig. 1 between the lines X—X and Y—Y, an increase in signaling speed up to about 50 cycles per second was obtained.

5 With this arrangement, as the signaling speed was increased above 50 cycles per second, there was a tendency for the components of the signaling current which were slightly lower than the reversal frequency, 10 to become excessive and so distort the shape of the receiving signals. In order to overcome this difficulty, the auto-transformer 30 was inserted, as shown in Fig. 1. With 15 this arrangement, code messages have been received over the New York-Azores loaded cable at signaling speeds up to 60 cycles per second. The indications are that higher speeds could be attained providing the interference due to extraneous sources, such as 20 power and lighting circuits, and natural electrical disturbances could be eliminated or reduced.

One or more additional shaping networks, similar to network N² but differently 25 adjusted, could be used if the service conditions warranted. Such networks might replace auto-transformer 30. Each would be effective to suppress certain of the lower 30 frequency components of the signal and each would be most effective at a particular frequency or range of frequencies.

The signaling speed of 60 cycles per second was obtained with an adjustment of the 35 circuit elements of Figs. 1 and 2 as follows: Sending resistance 18, 17 ohms; sending condenser 19, 40 microfarads; sending shunt resistance 20, 10,000 ohms; sending shunt resistance 21, 80 ohms; battery voltage, 60 volts; signaling speed, 40% 40 marking, 60 cycles per second.

Network N³—Inductance 37, 6.5 henrys; condenser 36, 0.17 microfarads.

Network N²—Inductance 34, 150 henrys; condenser 33, 0.4 microfarads; resistance 35, 7000 ohms.

Network N¹—Condenser 31, 6.8 microfarads; resistance 32, 15,000 ohms; coupling resistance 28, 1500 ohms; damping resistance 29, 90,000 ohms; total number of turns in auto-transformer 30, 11,000 turns; primary turns of auto-transformer 30, 2000 turns; interstage coupling resistances 52, 60 and 68, each 192,000 ohms.

Network 51—Primary condenser 54, 0.03 microfarads; primary inductance of auto-transformer 57, 60 henrys; primary resistance of auto-transformer 57 and resistance 56, 200,000 ohms; total inductance of auto-transformer 57, 10,000 henrys; secondary condenser 55, 100 micro-microfarads.

Network 59—Potentiometer 64, 2 megohms; inductance 62, open circuited; resistance 66, 125,000 ohms; condenser 63, 0.01 microfarads.

65 Network 67—Resistance 72 (not adjust-

able), 2 megohms; inductance 70, open circuited; resistance 74, 125,000 ohms; condenser 71, 0.01 microfarad.

As an alternative to the preferred sending circuit of Fig. 1 that of Fig. 10 may be 70 used. It is similar to the sending arrangement of Fig. 1 except that the comparatively low resistance 21 of Fig. 1 has been replaced by the series resonant network N⁵ 75 consisting of condenser 90, inductance 91, 75 series resistance 92, and shunt resistance 93. The network N⁵ is adjusted to offer a low 80 impedance to the frequency components of the signal which are least attenuated by the other portions of the cable system. While 85 this arrangement shows improvements over systems heretofore known, it is less desirable than the arrangement of Fig. 1 as it does not give as good results due to the fact that it causes partial oscillations to be superposed on the signal and also introduces distortion due to hysteresis in the coil 91.

Still another alternative sending circuit 90 which is preferable to that of Fig. 1 under some operating conditions is shown in Fig. 11. This circuit is identical with that of Fig. 1 except that a very large condenser 95 of several hundred microfarads is inserted in series with sending shunt resistance 21. This condenser is so large that it has little 95 influence on the action of the shunt resistance at any but the extremely low frequency components of the signal.

As hereinbefore explained the low resistance shunt 21 is important in high speed 100 working, since it greatly increases the effectiveness of the usual sending condenser, but it has the disadvantage of shunting to earth the larger part of the extremely low frequency components of the transmitted signal, 105 thereby requiring that the series condenser at the receiving end of the cable be shunted by a relatively low resistance. Such a low resistance at the receiving terminal is objectionable, since it permits a rather strong 110 earth current to flow through the shaping network which is located between the cable and the amplifier. The establishment of this earth current during switching from sending to receiving produces a heavy surge 115 through the amplifier and momentarily displaces the zero of the signal. The insertion of the large condenser 95 materially reduces the strength of earth current and switching surges by permitting the use of a much higher resistance shunt on the receiving condenser.

In connection with the operation of printing telegraph equipment over the cable between New York and the Azores, it was found 125 that the use of condenser 95 in series with resistance 21 permitted the value of the resistance shunt 32 on condenser 31 at the receiving station to be increased from 15,000 ohms to 250,000 ohms. The corresponding 130

reduction in the strength of the earth currents affecting the receiver greatly increased the reliability of operation of the system.

The arrangements hereinbefore described have all been tried in connection with a submarine cable loaded with nickel-iron alloy which extends between New York and the Azores. Code signals have actually been transmitted over this cable and received in perfectly intelligible form at a signal speed of 60 cycles per second by means of the arrangements shown in Figs. 1 and 2.

The invention is not limited to the specific arrangement and values hereinbefore given, but is capable of considerable modification within the scope of the invention as defined by the appended claims.

What is claimed is:

1. A cable signaling system comprising a cable, an impulse transmitter connected to said cable through a sending condenser, and a path to earth having an impedance low in comparison with the characteristic impedance of the cable connected at a point between said cable and said condenser.

2. In a cable signaling system, a cable, transmitting apparatus connected thereto comprising an impulse transmitter and a shunted sending condenser connected in series, and a low resistance connected to said cable in shunt to said transmitting apparatus.

3. A submarine cable signaling system comprising a submarine cable, an impulse transmitter connected to said cable through a sending condenser, and a resistance path to earth connected at a point between said cable and said condenser and having a low value compared with the characteristic impedance of the cable.

4. A cable signaling system comprising a cable, an impulse transmitter connected to said cable through a sending condenser, and a path to earth connected at a point between said cable and said condenser, said path consisting of a highly damped series resonant circuit tuned to a frequency within the range of frequencies essential to signaling.

5. In a submarine signaling system, a submarine cable, signaling apparatus associated therewith, the characteristics of said cable and said apparatus being such that certain frequency components of the signaling current are transmitted thereover with less attenuation than other frequency components and a path to earth connected at a point between said signaling apparatus and said cable, said path consisting of a highly damped series resonant circuit tuned to said certain frequency components.

6. A submarine cable signaling system comprising a submarine cable loaded with an alloy of nickel and iron having high permeability at low magnetizing forces, an impulse transmitter connected to said cable

through a sending condenser, and a resistance path to earth connected between said cable and said condenser of low value compared with the characteristic impedance of the cable.

70

7. In a cable signaling system, a cable signaling apparatus associated therewith, the characteristics of said cable and said apparatus being such that certain frequency components of the signaling current are transmitted thereover with less attenuation than other frequency components, and a network comprising an anti-resonant circuit tuned to said certain frequency components connected in series with said cable at one terminal thereof.

75

8. In a submarine signaling system, a submarine cable system including a submarine cable and transmitting and receiving equipment connected thereto which transmits with less attenuation components of the signaling current somewhat below the signaling frequency, and a highly damped anti-resonant circuit connected in series with the signaling current path and tuned to a frequency also somewhat below the signaling frequency.

85

9. In a submarine signaling system, a submarine cable, sending equipment including a series shunted condenser and receiving equipment also including a series shunted condenser so proportioned as to transmit with least attenuation components of the signaling current somewhat below a predetermined signaling frequency, and a highly damped anti-resonant circuit connected in series with the signaling current path and tuned to the frequency of said least attenuated components.

95

10. In a submarine signaling system, a submarine cable, a receiving device having an input circuit for received signaling current, a resistance connected in shunt to said input circuit, and an anti-resonant circuit connected in series with the signaling current path between said cable and said resistance and tuned to a frequency somewhat below the signaling frequency.

100

11. In a submarine signaling system, a submarine cable, receiving apparatus comprising an electron discharge amplifier, a transformer for impressing signaling current upon the input circuit of said amplifier, a resistance connected in shunt to the primary winding of said transformer, and a highly damped anti-resonant circuit connected in series with the signaling current path between said cable and said resistance and tuned to a frequency below the signaling frequency.

115

12. In a submarine signaling system, a submarine cable, a receiving device having an input circuit for received signaling current, said input circuit being connected between said cable and ground, an auto-transformer connected in series with said input

120

125

130

- 5 circuit, a resistance connected in parallel to both said input circuit and auto-transformer, and a connection from the intermediate terminal of said auto-transformer to said 5 resistance.
- 10 13. In a submarine signaling system, a submarine cable, a receiving device having an input circuit for receiving signaling current, said input circuit being connected between said cable and ground, an auto-transformer connected in series with said input circuit, a resistance connected in parallel to both said input circuit and auto-transformer, and a connection from the intermediate 15 terminal of said auto-transformer to an intermediate point of said resistance.
- 15 14. Shaping apparatus for a submarine signaling system, comprising an auto-transformer, a resistance in series with the primary winding of said auto-transformer, a second resistance shunted around said primary winding, signal receiving apparatus connected between said series resistance and the secondary winding of said auto-transformer, whereby the voltage induced in the secondary winding may be adjusted to oppose the voltage across said series resistance and the primary winding to any desired extent and for any desired range of 20 frequencies.
- 20 15. In a submarine signaling system, a submarine cable, a receiving device comprising an electron discharge amplifier having shaping networks for changing the relative amplitudes of the several components of the 25 signaling current, a transformer for impressing signaling current upon said amplifier, and a shaping network connected between said cable and the primary winding of said transformer comprising an anti-resonant circuit for reducing interfering current of a frequency above the frequencies 30 essential to signaling, a second anti-resonant circuit for reducing the effect of signaling current of a frequency within the range of essential signaling frequencies, and a shunted condenser for reducing the effect 35 of current of very low frequencies within the range of essential signaling frequencies.
- 35 16. A submarine cable loaded with an alloy of nickel and iron having high permeability at low magnetizing forces, signaling apparatus associated therewith, the characteristics of said cable and said apparatus being such that certain frequency components of the signaling current are transmitted thereover with less attenuation than other frequency components, and a network comprising a highly damped anti-resonant circuit tuned to said certain frequency components connected in series with said cable at one terminal thereof.
- 40 17. A submarine cable loaded with an alloy of nickel and iron having high permeability at low magnetizing forces, sending equipment including a series shunted condenser and receiving equipment also including a series shunted condenser so proportioned as to transmit with least attenuation components of the signaling current somewhat below a predetermined signaling frequency, and a highly damped anti-resonant circuit connected in series with the signaling current path and tuned to the frequency of said least attenuated components.
- 45 18. A submarine cable loaded with an alloy of nickel and iron having high permeability at low magnetizing forces, receiving apparatus comprising an electron discharge amplifier, a transformer for impressing signaling current upon the input circuit of said amplifier, a resistance connected in shunt to the primary winding of said transformer, and a highly damped anti-resonant circuit connected in series with the signaling current path between said cable and said resistance and tuned to a frequency lower than the signaling frequency.
- 50 19. A submarine cable loaded with an alloy of nickel and iron having high permeability at low magnetizing forces, a receiving device having an input circuit for receiving signaling current, said input circuit being connected between said cable and ground, an auto-transformer connected in series with said input circuit, a resistance connected in parallel to both said input circuit and said auto-transformer, and a connection from the intermediate terminal of said auto-transformer to an intermediate 55 point of said resistance.
- 55 20. A submarine cable loaded with an alloy of nickel and iron having high permeability at low magnetizing forces, a receiving device comprising an electron discharge amplifier having shaping networks for changing the relative amplitudes of the several components of the signaling current, a transformer for impressing signaling current upon said amplifier, and a shaping network connected between said cable and the primary winding of said transformer comprising a sharply tuned anti-resonant circuit for reducing an interfering current of a frequency above the frequencies essential to signaling, a highly damped anti-resonant circuit for reducing the effect of signaling currents of a band of frequencies within the range of essential signaling frequencies, and a shunted condenser for reducing the effect of current of very low frequency within the range of essential signaling frequencies.
- 60 21. In a cable signaling system comprising a cable, an impulse transmitter connected to said cable through a sending condenser, and a path to earth having an impedance low in comparison with the characteristic impedance of the cable connected

at a point between said cable and said condenser, said path comprising a low resistance and a large condenser.

22. In a cable signaling system, a submarine cable, transmitting apparatus connected thereto comprising an impulse transmitter and a shunted sending condenser connected in series, and a series circuit connected to said cable in shunt to said

transmitting apparatus, said circuit comprising a low resistance and a condenser so large that its effect upon said series circuit except at very low frequencies is negligible.

In witness whereof, I hereunto subscribe my name this 15th day of September, A. D., 15 1925.

AUSTEN M. CURTIS.
